UNITED STATES PATENT OFFICE.

BERT CLEMENT BERRY, OF CALGARY, ALBERTA, CANADA, ASSIGNOR TO BERRY SHOCKER INCORPORATED, OF WILMINGTON, DELAWARE, A CORPORATION OF DELAWARE.

SHOCKER.

Application filed August 20, 1919. Serial No. 318,738.

My invention relates to improvements in shockers; and the object of the invention is to devise a shocker which will be simple in construction and in which the sheaf receiving pan may be operated to up end the shock without the employment of gears to perform the upending operation. The upending of the shock is effected by a forward rotation of the pan which serves to butt the shock firmly upon the ground, and thereafter the pan continues its rotation over the top of the shock and around to its normal position, effecting a complete revolution during the cycle. This revolution of the pan is effected by ground engaging treads which, when the pan is filled, are lowered into ground engagement so that a dumping operation is effected directly by ground contact and without the use of gears or similar transmission connections.

The invention consists essentially in the arrangement and construction of parts as hereinafter more particularly explained.

In the drawings:

Figure 1 is a side elevation of my shocker device showing the parts in normal position in full lines and in intermediate position in dotted lines;

Fig. 2 is a similar view to Fig. 1, showing the parts in the position they assume when the shock is upended in full lines and in the returning position in dotted lines;

Fig. 3 is a plan view of the shocker device showing its connection to the binder;

Fig. 4 is an end elevation of the shocker device and its connection to the binder frame.

Figs. 5, 6, 7, 8 and 9 are diagrammatic views showing the successive positions assumed by the pan in discharging the shock to the ground and Fig. 10 is a perspective view of the forward end of the sheaf receiver and associated threads.

In the drawings, like characters of reference indicate corresponding parts in the various figures.

1 represents the frame of the machine, which comprises two side rails 2 and 3 and a cross connecting bar 4, making the main portions of the frame U shape. The forward right hand side of the machine is supported by a wheel 5, and the rear right side by a swivel castor wheel 6. The left side of the frame 1, formed by the bar 2, is connected to

the binder by a bracket 7 of suitable construction.

8 indicates the main wheel of the binder, and 9 the binder deck indicated by dotted lines in Fig. 3. 10 and 11 indicate pivot bolts upon which are swingingly mounted, at one end, bars 12 and 13.

The bars 12 and 13 are each preferably formed by two bar members 12^x and 12^y and 13^x and 13^y, through which the pivot bolts extend and are separated by suitable spacers 14 and 15, as shown in Fig. 3. It will thus be seen that the swinging bars 12 and 13 are swung at each side of the frame 1 and pivoted near the forward end thereof, the rear end being free to swing toward and from the ground. This construction forms in effect a pivoted inner frame which serves as a vertical swinging support for the pan or sheaf receiver presently to be described.

By reason of the bars 12 and 13 comprising bar members which are separated by spacers, each bar will be provided with elongated slots 16 and 17 extending longitudinally of the bars and in parallel relation to the side bars or rails of the main frame.

The pivoted bar members, which comprise in effect the swinging inner frame, are normally held in raised position by means of triggers 18 and 19, each provided with a ratchet shaped notch 18^x on its forward face, as indicated in dotted lines in Figs. 1 and 2. The upper ends of the triggers are pivotally supported upon bolts 20 and 21 extending inwardly from the side rails 2 and 3 of the main frame, the lower ends of the triggers being free to swing fore and aft. The triggers depend downwardly through the slot openings 16 and 17 near the rear or free ends of the pivoted bars 12 and 13 comprising the swinging frame, and the triggers are actuated by means of trigger release arms 22 and 23 pivoted at the rear end of the main frame intermediate of their length upon pivot bolts 24 and 25 inwardly extending from the rear ends of the side rails 2 and 3 of the main frame.

The upper ends of the release arms 22 and 23 are united by a cross rod 26 elevated above the main frame, which causes them to swing in unison, and which cross rod is provided with a hand push bar 27 extending rearwardly therefrom in proximity to the driv-

er's seat on the binder and in convenient relation to be operated manually by the driver. The lower ends of the arms 22 and 23 are connected by links 28 and 29 to the lower 5 ends of the trigger bars 18 and 19, so that a forward thrust of the cross rod will result in a retraction of the two trigger bars. Each pivoted side bar 12 and 13 is provided with a roller 30 which normally rests within the 10 notch 18^a of the proximate trigger bar 18, so that a rearward retraction thereof will release the forwardly pivoted bars 12 and 13 and allow the rear ends to fall. This 15 releasing action is effected against the tension of springs 31 which connect the trigger release arms 22 and 23 to the proximate side rails of the main frame.

The bars 12 and 13 which comprise the swinging inner frame are provided with inwardly extended stub axles located near the center thereof, which stub axles afford trunnions for the mounting of the sheaf receiver 34 which is supported within a frame or cradle consisting of upper rails 35^a and lower 20 rails 35^b with cross straps 35^c connecting with the sheaf receiver. The cradle is hung from the stub axles 32 and 33, as best indicated in Fig. 4. The sheaf receiver is trough-shaped and tapered from the front to the 25 rear and also from the top to the bottom and is open at both ends, so that when in its normal or receiving position it will receive the sheaves butt-end forward and in longitudinal 30 relation to the machine.

35 A revolution of the sheaf receiver is effected through the action of arc-shaped tire members 35 and 36 rigidly secured to the frame or cradle, so that the rotation of the tire members by contact with the ground 40 will effect a complete revolution of the sheaf receiver mounted upon its axles or trunnions. The arc-shaped tire members are positioned in generally eccentric arrangement to the axis of the sheaf receiver, and the major 45 radial dimension of the tire members is in a plane transverse to the plane of the open side of the sheaf receiver; that is to say, the tread portions of the tire members, at a point in immediate opposition to the open 50 side of the sheaf receiver, will be more distantly located from the axis of movement than at any other point, so that in the revolution of the sheaf receiver the ground contact of the tire members will lift the axis of the 55 sheaf receiver to its highest point when the sheaf receiver is in overturned position and at the time when the sheaf receiver is somersaulting forward to clear the deposited shock. The tire members 35 and 36 are 60 provided with tooth projections or spuds 37^a or other suitable means for gripping the ground when the tires are brought into contact therewith.

65 The sheaf receiver is provided at its rear end with stop projections 37 and 38 which

engage with the inwardly projecting ends of the stud shafts 24 and 25 which serve to limit the upwardly swinging return movement of the sheaf receiver after it is brought back to normal position. The relation of 70 the stop projections 37 and 38 and the studs 24 and 25 is such that when the axis of revolution of the pan is elevated, as in the sheaf receiving position shown in Fig. 1, the stop projections will slightly engage the 75 under side of the stud shafts, but when the notched triggers are withdrawn and the loaded sheaf receiver is dropped to the position indicated in dotted lines, the stop projections will be swung forward sufficiently 80 to clear the studs on the upward rotating movement of the rear end of the pan. That is to say, the weight of the grain within the sheaf receiver will cause the pan to drop and pitch slightly forward until the tire members 85 engage the ground, and this movement is sufficient to enable the stop members to clear one another. On the return movement, however, the final momentum of the pan, after the discharge of its load, will be sufficient to swing the rear end of the pan upwardly until the stop members engage one another, in which position the latch trigger 90 will engage to prevent the inner pivoted frame from falling back into ground contact while the preponderance of weight at the enlarged forward end of the pan will maintain the stop members in engagement.

95 The side rails 12 and 13 have secured thereto cams 39 and 40 provided with inwardly opening opposing camways 41 which furnish endless cam contact faces 42 and 43, as indicated in section at the upper portion 100 of Fig. 3. 44 indicates a rocking cross rod extending between and pivoted through companion bars 45 and 46, each bar being secured at its inner end to the proximate cradle rail 35^a adjacent the rim of the sheaf receiver and extending in right angle relation 105 away therefrom toward the tire member to which it is secured, which arrangement furnishes a pivotal mounting for the ends 110 of the cross rod, which rod extends across the open side of the sheaf receiver at a point near the enlarged forward or butt receiving end thereof. The ends of the pivoted cross rod are provided with crank arms 47 and 48, each carrying a cam roller which extends into the adjacent camway 41 and alternately engages the cam surfaces 42 and 43 as the sheaf receiver is overended to discharge the shock. The cam surfaces 42 and 43 are so shaped as to coact with the cam rollers 49 to exert a constant rearward pressure 115 upon the shock as the same is being discharged by means of a spring held arm 50 which is swung rearwardly by the rotating of the rod 44 as the sheaf receiver is carried 120 to the discharging position, which rearward pressure counteracts the tendency of the 125 130

shock to topple forwardly when butted on the ground.

- In operation, the sheaves are discharged from the binder deck 9 into the upwardly opening receiver 34 with the butts extending forwardly, the receiver being tapered from front to rear in order to allow the butts to spread so as to give the shock a firm hold on the ground when upended.
- When the required number of sheaves have been deposited in the receiver the push bar 27 is thrust forwardly by the operator of the binder, thereby rocking the trigger release arms 22 and 23 upon their supporting stud shafts 24 and 25 in the direction of the arrow (see Fig. 1) against the tension of the springs 31. By this means, through the link bars 28 and 29, the trigger bars 18 and 19 are swung rearwardly, thereby carrying the notches 18* from beneath the rollers 30, which releases the rollers and allows the rear ends of the bars 12 and 13 comprising the inner swinging frame to swing downwardly on their forward pivots. The weight of the grain in the receiver, and the distribution of the weight, is such as to cause the forward end of the receiver and the corresponding portion of the tire member to engage the ground, as indicated in dotted lines in Fig. 1. The continued advance of the shocker then causes the sheaf receiver to rotate with its pivot in the lowered position, in which position the stops at the rear end will clear the stud shafts 24 and 25 and the rotation will continue throughout the cycle. When the parts have reached the vertical position illustrated in full lines in Fig. 2 and Fig. 6, the shock will be butted on the ground, and the free end of the pressure arm 50 will be drawn back into firm contact with the middle of the shock by the action of the rollers on the crank arms 47 with the corresponding cam surfaces. With the parts in this position, the rod 44 will bear against the base of the shock at a point slightly above the ground. This holds the shock steady while the sheaf receiver is moving from the position indicated in Fig. 6 to that shown in Fig. 7 which constitutes the critical point in the deposition of the shock on the ground. Although the machine as a whole is forwardly advancing, the base portion of the receiver at its discharging end will swing backwardly with respect to the machine, and upwardly over the rear upper face of the deposited shock so as to substantially clear the shock at this point without appreciable interference, the shock meanwhile being steadied by the contact of the pressure arm 50 and the cross bar 44.

As the sheaf receiver continues its rotation to the position shown in Fig. 8, it will somersault over the deposited shock, and this action is facilitated by the configura-

tion of those portions of the tire members which lie adjacent to the open side of the sheaf receiver. These portions of the tire members, being outwardly bowed to a greater extent from the center of rotation 70 than other portions of the tire member, will bodily lift the sheaf receiver when in its overturned position, thereby enabling it better to clear the deposited shock without tending to upset the same. 75

The tire members will continue their engagement with the ground until the sheaf receiver has swung almost back to its normal position, at which point the termination of the tire members is reached and the 80 ground contact ceases. However, at this point the pan will have acquired sufficient rotative momentum to cause its rear or reduced end to swing upwardly, which upswinging is facilitated by the disposition of the weights of the pan on opposite sides of its pivotal axis, and the momentum also lifts the free ends of the pivoted swinging inner frame bars 12 and 13 sufficiently to latch the same concurrently with the stopping of the rear end of the pan by contact of the stop members. The cycle of operations is thus completed with the pan again in its receiving position with its open side upward. 85

It will be observed that ground contact of the tire members is continuous throughout the entire butting operation, so that means are afforded for positively carrying the pan completely over the shock in accurately 100 timed relation to the advance of the machine, and at the same time, by providing tire members of the character indicated, the somersaulting movement of the pan can be accurately regulated to afford the necessary 105 clearance between the pan and the deposited shock at all points during the cycle of operations. As a result of this arrangement, the only pressure which will be brought to bear upon the shock will be direct, by the pressure arm 50, against the middle of the shock, and it is desirable that the cams which control the movements of the pressure arm be configured to cause the free end of the pressure arm to travel rearwardly in an arcuate movement with sufficient speed to continue this contact at the middle portion of the shock until the same is firmly butted, and the tendency to overturn, caused by the forward momentum of the mass of 110 grain, has been overcome. At the same time the contact of the cross rod or rock shaft 44 against the base of the shock will be relieved and compensated by the forward advance of the machine, so that the swinging movement of this rod will not have a tendency to trip under the base of the shock and thereby overturn the same. 115

I claim:

1. In a shocker, a supporting member 130

adapted to be raised and lowered, a sheaf receiver pivoted in the supporting member, and a ground engaging member associated with the sheaf receiver and adapted to be brought into ground contact by the lowering of the supporting member to upend the shock.

2. In a shocker, a supporting member adapted to be raised and lowered, a sheaf receiver pivoted in the supporting member,

10 and a ground engaging member associated with the sheaf receiver and adapted to be brought into ground contact by the lowering of the supporting member to upend the shock, said ground engaging member being configured to maintain ground contacts throughout the entire period required in depositing the shock and carrying the receiver over the deposited shock.

15 3. In a shocker, a supporting member adapted to be raised and lowered, a sheaf receiver pivoted in the supporting member, and a ground engaging member associated with the sheaf receiver and adapted to be brought into ground contact by the lowering of the supporting member to upend the shock, said ground engaging member being configured to maintain ground contact throughout the entire period required in depositing the shock and carrying the receiver over the deposited shock, and configured to elevate the pivotal mounting for the sheaf receiver at the time when the sheaf receiver is clearing the top of the deposited shock.

20 4. In a shocker, the combination of a sheaf receiver, releasable means for pivotally supporting the sheaf receiver, means for releasing such supporting means, and a tire member associated with the sheaf receiver and adapted to be carried into engagement with the ground to upend the sheaf receiver by the forward travel of the shocker.

25 5. In a shocker, the combination of a sheaf receiver, means for supporting the sheaf receiver, means for releasing such supporting means, means adapted to be carried into contact with the ground by the release of the sheaf receiver supporting means to upend the receiver by the forward travel of the shocker, a pressure member and means for moving the pressure member to position to bear against the shock during the setting up of the shock.

30 6. In a shocker, the combination of a member pivotally supported at one end and releasably supported at a point removed from the pivotal point, a sheaf receiver swung from the pivotally supported member, and a curved tire member carried by the sheaf receiver and adapted to engage the ground when the pivotally supported member is released.

35 7. In a shocker, the combination of a member pivotally supported at one end and releasably supported at a point removed from

the pivotal point, a sheaf receiver swung from the pivotally supported member, a curved tire member carried by the sheaf receiver and adapted to engage the ground when the pivotally supported member is released, said tire member being configured to lift the pivotal support for the sheaf receiver at a point coincident with the movement of the sheaf receiver over the top of the deposited shock.

40 8. In a shocker, the combination of spaced members pivotally supported forward and releasably supported at a point removed from the pivot point, a sheaf receiver swung between the pivotally supported members, curved tire members carried by the sheaf receiver and adapted to engage the ground when the pivotally supported members are released, and means for limiting the return movement of the sheaf receiver.

45 9. In a shocker, the combination of a main frame, members pivotally supported in the main frame and releasably supported at a point removed from the pivot point, a sheaf receiver pivotally mounted between such members, means carried by the sheaf receiver and adapted to engage the ground and rotate such receiver by the forward travel of the machine when the pivotally supported members are released, the sheaf receiver being adapted to be returned to its normal position after the deposit of a shock.

50 10. In a shocker, the combination with a main frame of spaced bar members pivoted forwardly to the main frame, a latch for supporting the spaced members in their normal position, a sheaf receiver pivotally mounted between the spaced members, and means associated with the sheaf receiver for engaging the ground when the spaced members are released for turning the sheaf receiver to upend the shock and for automatically effecting the return of the spaced members to their latch engaging position.

55 11. In a shocker, the combination with a main frame of spaced members pivotally supported forwardly in the main frame, a latch member provided with a notch, a projection carried by the pivoted bars and adapted to engage such notch, means for disengaging the projection from the notch, a sheaf receiver pivotally mounted between the bar members, and a tire member carried by the sheaf receiver and adapted to be carried into engagement with the ground by the release of the bar members to rotate the sheaf receiver by its engagement with the ground and to effect a return movement of the spaced members to their normal position to engage the latch members.

60 12. In a shocker, the combination of a main frame, spaced members pivotally supported at one end on the main frame, spring held latch bars pivoted at their upper ends to the main frame and each provided with

70

75

80

85

an edge notch, a projection carried by each of the pivotal spaced members adapted to engage such notch, means for withdrawing the spring held latch bars to release the projections, a sheaf receiver pivotally mounted between the spaced pivotal members, a tire member carried by the sheaf receiver and adapted to be carried into engagement with the ground by the release of the spaced members to rotate the sheaf receiver by its engagement with the ground and to cause an ultimate lifting of the spaced members back to their normal position to engage the latch bars, a pressure arm adapted to engage the shock, and means for forcing the pressure arm into engagement with the shock during the upending of the shock.

13. In a shocker, the combination with a main frame of a sheaf receiver, releasable means for pivotally supporting the sheaf receiver within the main frame, and means adapted to be carried into contact with the ground by the release of the sheaf receiver

supporting means to upend the receiver by the forward travel of the shocker. 25

14. In a shocker, the combination with a main frame of a sheaf receiver, releasable means for pivotally supporting the sheaf receiver within the main frame, means adapted to be carried into contact with the ground 30 by the release of the sheaf receiver supporting means to upend the receiver by the forward travel of the shocker, a pressure arm, actuating members for said pressure arm, cam surfaces adapted to be engaged 35 during respective portions of the rotation of the sheaf receiver by said actuating members, and adapted to cause pressure of said arm against the shock during the turning of the sheaf receiver to upended position, said 40 cam surfaces being also adapted to cause release of said pressure arm and the return thereof to normal position during continued turning of the sheaf receiver.

BERT CLEMENT BERRY.
